CLAIM

The ornamental design for a gaming machine, as shown and described.

DESCRIPTION

FIG. 1 is a right perspective view from the front and above a gaming machine showing the new design.

FIG. 2 is a front view of the gaming machine shown in FIG. 1.

FIG. 3 is a rear view of the gaming machine shown in FIG. 1.

FIG. 4 is a left side view of the gaming machine shown in FIG. 1.

FIG. 5 is a right side view of the gaming machine shown in FIG. 1.

FIG. 6 is a top view of the gaming machine shown in FIG. 1.

FIG. 7 is a bottom view of the gaming machine shown in FIG. 1.

FIG. 8 is an enlarged perspective view of the gaming machine portion called out in FIG. 1; and,

FIG. 9 is an enlarged perspective view of the gaming machine portion called out in FIG. 2.

The dotted lines shown in the drawings depict portions of the gaming machine that form no part of the claimed design.

The symbol consisting of a hexagon shape that is split down the middle vertically with a letter "E" within the center of the hexagon is a trademark of "Everi Games, Inc.", and forms no part of the claimed design. The short-long dash lines illustrate boundary line which define the bounds of the claim. The remaining dotted broken lines depict portions of the gaming machine that form no part of the claimed design.

1 Claim, 7 Drawing Sheets
